UNITED STATES PATENT OFFICE

CHARLES S. BURTON, OF OAK PARK, ILLINOIS, ASSIGNOR TO STEWART-WARNER CORPORATION, OF CHICAGO, ILLINOIS, A CORPORATION OF VIRGINIA

REBOUND CHECK FOR VEHICLES

Application filed January 24, 1923. Serial No. 614,668.

The purpose of this invention is to provide an improved construction of rebound checks for vehicles adapted to afford spring and friction resistance to the rebound of the vehicle after the depression incident to the dropping of the wheels into a depression in the road and adapted also to afford frictional resistance to the descending movement of the vehicle under such circumstances and adapted also to be constructed more economically than previous devices of this character. It consists in the elements and features of construction shown and described as indicated in the claims.

In general the device consists of a drum or pulley formed of two members, one cup-shaped and the other a cap for the cup journaled on a fixed stud or center post, which constitutes the means of mounting the device upon the vehicle body or axle; a helically coiled spring within the drum having the inner end connected to the journaled stud and the outer end connected to the drum; a casing which encloses the drum on the journal stud comprising two members, one a cup shaped stamping and the other a cap or closure for the open end of the cup; self-lubricating friction disks interposed at opposite sides of the drum between the same and the opposite walls of the casing; a flexible strap secured to and wrapped about the drum and emerging through a peripheral opening in the casing; the casing as well as the drum being adapted to be entered onto the stud from the free end,—that is, the end opposite that by which it is attached to the vehicle axle or body; the attaching bracket or mounting piece constituting a stop against which all the parts entered on the stud are stopped longitudinally of the stud; a spring being provided on the outer ends of the stud for pressing against the outer side of the casing to yieldingly compact all the elements in the casing together and against the stop shoulder of the mounting piece or bracket, and a nut on the outer end of the stud for tensioning this laterally stressing spring to regulate the friction for resisting the rotation of the drum.

Referring to the drawings:—

Figure 1 is an axial section of the entire device cutting through the opening through which the strap emerges.

Figure 2 is a section at the line, 2—2, on Figure 1, being trans-axial of the entire device.

Figure 3 is a detail right hand side elevation of the central portion of the device broken out from the remainder, showing the mounting piece or bracket in its engagement with the cup member of the casing.

Figure 4 is a detail plan view of a link for connecting the outer end of the helical spring with the drum.

Figure 5 is an elevation of the cup member of the casing looking into it from the open end or side.

Figure 6 is an elevation through an inner and outer side of the cover member of the casing.

Figure 7 is an elevation of the cup member of the drum looking into it from the open side.

Figure 8 is an elevation of the cover member of the drum.

In these figures B is the journal stud reduced in diameter at the inner end and threaded at B¹, for screwing into the mounting piece or bracket, A which may be of any convenient form suitable for attaching to the vehicle body or axle according to the circumstances and form of the part to which the attachment is to be made. The threaded boss form of this device, as shown, is not obligatory, but the radially projecting fingers or lugs A¹, or the equivalent of them for engaging the casing as shown, and hereinafter described, constitute an important feature of this bracket or mounting piece. The journal stud, B, is screwed tight into the mounting piece, A, bringing the shoulder, B, tight against the latter. The cup member, D, of the casing having a central aperture for admitting the journal stud, B, is next passed onto the stud back against the bracket or mounting piece, A; and this cup member being a stamping is provided with outwardly struck bosses, D¹, between which the fingers, A¹, of the bracket become engaged when

the casing is introduced onto this journal stud, as described.

The next in order of assemblage, the helical spring, G, is placed within the cup member, D, of the drum, its outer end being connected with the drum by the link, H, and the spacer sleeve, K, which is a split ring, is engaged with the inner hook end, G², of the spring; the cover member, c, of the drum is then applied, its radial projections, c¹, engaging the notches, c¹⁰, in the edge of the flange, C¹, of the cup member, C, of the drum; one of the self-lubricating disks, E, is applied on the outer face of the cover member, c, and the strap, F, is hooked at one end into the slot, C³, provided for that purpose in the flange, C¹, of the cup member of the drum and wrapped around the drum, and this assemblage of the drum, spring and spacing sleeve and strap is introduced onto the journal and into the casing, the inner coil of the helical spring being slightly sprung open to admit it in view of the hook end, G², which, however, readily snaps into the slot, B⁴, provided for it in the journal stud, or the slot B⁴, being extended to the end of the stud for convenience of introducing the hook of the spring. A second self-lubricating disk, E, is next applied against the outer side of the drum and the cover member, d, of the casing is introduced onto the journal, its radial projection, d¹, engaging the notches, D¹⁰, of the cup member of the casing; the spring, L, which is shown in the star form but which might be of any desirable form, is introduced onto the outer end of the stud and followed by the tensioning nut, M. If desired, an additional coil spring, N, may be provided and introduced under the star-shaped spring, L, or a suitably heavy coil spring such as N, may be employed alone for tensioning the lateral friction of the parts.

As shown, the drum members are both recessed on the outer sides to receive and position the self-lubricating parts, E; but this is not necessary since these parts, E, are definitely positioned by being centered on the annular bosses, C², and c², of the cup member and cover member respectively, of the drum.

In operation it will be seen that frictional resistance to the rotation of the drum in the casing may occur at both sides of the self-lubricating parts, E, that is, on the outer surfaces of the drum and on the inner surfaces of the casing.

The drum as well as the casing can be a stamping.

It will be understood that this spacer sleeve, K, is desirable, if not necessary, for the purpose of insuring against crushing or springing together the opposite sides of the drum by the pressure applied for lateral friction, and to insure that said pressure is transmitted to the inner self-lubricating disk or plate, E. It will be understood that

the thickness of the plates, E, should be slightly more than the height of the bosses, c² and C², so that the pressure applied for friction shall operate to press together the casing walls and the side walls of the drum without stoppage of the said casing wall against the said annular bosses, c² and C².

The operation of the device may be understood from the foregoing description of the construction to be, that the entire device having been mounted by means of the mounting member, A, upon the vehicle body, the strap, F, is withdrawn, rotating the drum for tensioning the spring, G, to any desired degree, and then secured to any convenient part of the chassis. When by jolting of the vehicle in travel over the road the body of the vehicle is lowered, tensioning the vehicle springs, the reaction of the coil spring, G, causes rotation of the drum which takes up the slack of the cable due to the lowering of the vehicle body; and upon the upward recoil of the body caused by the reaction of the vehicle springs or opposite jolting, the spring, G, due to its tension, tends to resist the unwinding of the strap by the upward movement of the vehicle body, and in the necessary unwinding of the strap, the spring is retensioned while the recoil is checked by its resistance, said recoil and unwinding being further checked by the resistance to the rotation of the drum due to the lateral friction between the drum and the enclosing wall of the case or the interposed friction plates or both.

I claim:—

1. In a device for the purpose indicated, a rotatable drum, a fixed journal bearing member for the drum, a spring connecting the drum with the journal bearing member for being tensioned by the rotation of the drum in one direction and for rotating the drum in the opposite direction by its reaction, a fixed casing enclosing the drum and spring, a flexible connector wrapped around the drum and secured thereto at one end, the other end emerging from the casing at the periphery of the latter, a friction plate loose on the journal bearing lodged in the casing between one side wall thereof and the adjacent side of the drum, the casing comprising a side plate which is movable along the axis relatively to the casing body and non-rotatably engaged with said body, and spring means for stressing the friction plate against the drum located exteriorly of the casing and reacting between the journal bearing and said movable side of the casing for pressing the latter against the drum.

2. In the construction defined in claim 1, foregoing, a second friction plate lodged within the casing between the other side wall thereof and the drum for frictioning against the opposite side of the drum.

3. In a device for the purpose indicated

5 a rotatable drum, a fixed journal bearing member for the drum, a spring connecting the drum with the journal bearing member for being tensioned by rotation of the drum in one direction and for rotating the drum in the opposite direction by its reaction, the drum comprising a cup member and a cap plate for closing the otherwise open side thereof, a spacing sleeve on the journal bearing between the bottom and the cap plate of the drum, the journal bearing member having a slot for engaging the inner coil of the spring, and the sleeve being par-axially slotted for registration with the journal bearing slot to admit the hook connection of the spring into said slot.

10 4. In the construction defined in claim 1, foregoing, the journal bearing member being extended to protrude from the casing at one side, and a mounting member with which said protruding end is adapted to be rigidly engaged, the casing wall at that side having exterior protuberances and the mounting member having lugs for engagement with said protuberances when the casing is held against the mounting member, the casing and the drum being adapted to slide along the journal bearing member, and the spring for pressing the friction plate 15 against the drum being outside the casing at the opposite side from that which has said protuberances for engaging the mounting member, and a stop on the opposite end of the journal bearing member between 20 which and the approximate wall of the casing said last mentioned spring is tensioned.

25 5. In the construction defined in claim 1, foregoing, the drum comprising a cup member and a cap member for closing the open side of the cup; a hook for attaching the outer end of the coiled spring to the drum consisting of a clip having at one end an aperture for hooking the spring to the link and at the other end opposite laterally protruding 30 pintles, the bottom disk of the cup and the cap plate having pivot apertures for engaging said pintles, the cup and the cap periphery having interlocking projections and recesses relatively positioned for engaging the cap 35 with the cup to position said pintle apertures directly opposite each other.

40 6. In the construction defined in claim 1, foregoing, a hook for engaging the flexible connector strap with the drum consisting of a metal clip folded to embrace the end of the strap and having hooks at its opposite sides at the folded end, the drum having eyes for engagement of said hooks positioned at opposite points adjacent to the side walls of the 45 drum in the zones between said side walls and the interiorly coiled spring.

45 7. In a rebound controller, a rotatable drum; a strap to be wound onto and unwound from the drum; a casing within which the 50 drum is mounted for rotation and between

whose side walls it is enclosed; a spring within the drum for winding the strap onto the drum and yieldingly resisting the unwinding, and a pair of friction members engaging respectively the opposite sides of the drum and the correspondingly opposite sides of the casing, whereby friction due to the rotation of the drum relatively to the casing is obtained at and distributed over four planes of contact of the friction members.

55 8. In a rebound controller, a drum; a strap adapted to be wound onto and unwound from the drum; a spring for rotating the drum in one direction so as to wind the strap thereon; self-lubricating members associated with the drum on opposite sides of the spring, and a casing composed of relatively movable parts having respectively opposite sides enclosing the spring and drum between them, and means for yieldingly pressing said casing 60 parts toward each other for pressing said opposite sides respectively toward the corresponding opposite sides of the drum.

65 9. In a rebound controller, a drum, a strap adapted to be wound onto the drum and to be unwound therefrom, and a spring for rotating the drum in one direction, and a casing in which the drum is enclosed between opposite side walls thereof, and self-lubricating disks mounted co-axially with the drum between the opposite sides of the drum and the correspondingly opposite side walls of the casing for frictional co-operation both with the drum sides and with the casing walls.

70 10. In a rebound controller, a rotatable drum, a strap adapted to be wound onto the drum and to be unwound therefrom, and a spring for rotating the drum in one direction, said drum being composed of a pair of side members and an intervening peripheral member adapted to receive the strap.

75 11. In a rebound controller, a rotatable drum; a strap adapted to be wound onto the drum and to be unwound therefrom; said drum being composed of opposite side walls and a peripheral wall, a spring mounted within the drum for rotating the drum in one direction, one of the side walls of the drum formed for engagement with the peripheral wall and adapted to be applied to 80 and engaged with the latter after the spring is mounted in the drum.

85 12. In a rebound controller, a rotatable drum, a strap adapted to be wound onto the drum and to be unwound therefrom, and a spring for rotating the drum in one direction, said drum being composed of a pair of side members and an intervening peripheral member to which the inner end of the strap and the outer end of the spring are attached.

90 13. In a rebound controller, rotatable parts comprising a drum, a strap adapted to be wound onto the drum and unwound therefrom; a spring for rotating the drum in one direction mounted within the drum, said ro- 95

tatable parts comprising a pair of self-lubricating members at opposite sides of the drum, the drum comprising a side which is removable from the remainder, said remainder having means for attaching the inner end of the strap and the outer end of the spring, the removable side being adapted to be applied together with one of the self-lubricating parts after the spring is inserted and attached.

- 10 14. In a rebound controller, a drum, a strap adapted to be wound onto the drum and to be unwound therefrom, and a spring for rotating the drum in one direction, a pair of
15 self lubricating side members mounted at opposite sides of the drum; means holding said members in frictional engagement with the drum sides and a peripheral member to which the inner end of the strap and the outer end of the spring are connected, the spring being housed within the drum.

In testimony whereof, I have hereunto set my hand at Chicago, Illinois, this 20th day of January, 1923.

CHARLES S. BURTON.
